UNITED STATES PATENT OFFICE

SAMUEL SEGAL, OF NEW YORK, N. Y.

REISSUED

LOCK.

1,065,848.

Specification of Letters Patent. Patented June 24, 1913.

Application filed December 3, 1912. Serial No. 734,743.

To all whom it may concern:

Be it known that I, SAMUEL SEGAL, a citizen of the United States, residing at New York city, in the county of New York and 5 State of New York, have invented new and useful Improvements in Locks, of which the following is a specification.

This invention relates to fastening devices for swinging or sliding doors and has for 10 its object to provide a simple and practically burglar-proof article of this character, that will effectually operate to prevent the door from being forced or pried open.

A still further object is to provide a device 15 of this character that may be used in combination with the ordinary key actuated lock now on the market.

To these ends the invention consists in the novel details of construction and combination 20 of parts more fully hereinafter described and particularly pointed out in the claim.

Referring to the accompanying drawings forming a part of this specification in which 25 like numerals designate like parts in all the views:—Figure 1 is a sectional view showing my improved fastening device secured in position on a door, the section being taken on the line 1—1 of Fig. 2. Fig. 2 is a horizontal cross sectional view taken on the line 30 2—2 of Fig. 1 and showing the device connected to an ordinary Yale lock. Fig. 3 is a detail perspective view of the keeper. Fig. 4 is a detail perspective view of the bolt.

35 My improved fastening device is composed of two principal parts namely, the keeper 1 which is secured to the edge of the door jamb 8, and the vertical bolt 3 mounted in a casing 4, which is secured to the door. 5. 40 The keeper comprises the angle plate 6 having the countersunk apertures 7, through which the fastening screws 9 pass and the ears 10, apertured as at 11, and adapted when in its closed position, to receive the bolt 3. The bolt preferably square in cross section, is conveniently supported and slidably mounted within the casing 4 and comprises the body portion 12, from the front of which projects the hooks 13 which are 45 adapted to engage within the apertures 11 of the keeper 1.

The bolt 3 is raised and lowered from within the room by means of the latch knob

14 which is provided on its inner end with an operating finger 15 which operates within 55 the slot 16 cut in the rear end of the bolt. A spring 17 held within the casing and engaging the rear end of the bolt, is adapted to hold the bolt in its raised position. 60

A lock 18, preferably of the Yale type and arranged in the outer end of the face of the door, is adapted to actuate the bolt from the outside by means of the key 19. This is accomplished by means of the connecting 65 bar 20 secured at one end to the lock barrel 21 and at its other end to the operating finger 22 which also operates within the bolt slot 16. The bolt 3, it will be noted, is also provided with the shoulders 23 which are 70 adapted to engage with the shoulders 24 formed on the inside of the casing for properly guiding the bolt in its up and down movement and for further securing the parts together in a rigid manner. 75

The action of the fastening device will be easily understood. When the door is closed the bolt hooks become engaged in the apertures of the keeper, thus keeping the door closed. Through the action of the knob 80 from within, or by the key from without the bolt hooks are disengaged from the keeper and the door is free to open.

From the foregoing it will be seen that by the use of a device constructed in accordance with my invention that a door may be securely fastened at a plurality of points by a vertical keeper and bolt and in such a manner that it will be practically impossible to separate the door from its sash without 90 first destroying the fastening means.

It is obvious that those skilled in the art may vary the details of construction and arrangements of parts without departing from the spirit of my invention and therefore I 95 do not wish to be limited to such features except as may be required by the claim.

What is claimed as new is:

A lock comprising a casing provided with 100 openings and having an interiorly located shoulder, a bolt slidably mounted in the casing along said shoulder and having hooks adapted to move transversely across said openings, said bolt being provided with a slot located at its inner edge, a spring 105 located in the casing and bearing against the

bolt to hold the same against the shoulder, said spring adapted to enter the slot to hold the hooks beyond the edges of the openings, and a member mounted for turning movement in the casing and having a finger adapted to enter the slot to move the bolt along the shoulder.

In testimony whereof I affix my signature in presence of two witnesses.

SAMUEL SEGAL.
